F. DAVISON.
SUPPORT FOR BABY FEEDING BOTTLES AND TOYS.
APPLICATION FILED NOV. 9, 1920.

Patented Nov. 14, 1922.

UNITED STATES PATENT OFFICE.

FRANK DAVISON, OF DETROIT, MICHIGAN.

SUPPORT FOR BABY-FEEDING BOTTLES AND TOYS.

Application filed November 9, 1920. Serial No. 422,850.

To all whom it may concern:

Be it known that I, FRANK DAVISON, a subject of the King of Great Britain, residing at Detroit, in the county of Wayne 5 and State of Michigan, have invented certain new and useful Improvements in Supports for Baby-Feeding Bottles and Toys, of which the following is a specification.

This invention relates to improvements

- 10 in supports of the type utilized for holding bottles, and the primary objects of the present invention are to provide an improved device for holding nursing bottles in place for nursing, which is so constructed that the bottle can be moved to and held in any desired position against accidental displacement, which is most convenient for the infant, and according to the nature of the article or support with which the bottle is
- 15 to be associated; to provide means for permitting the device to be associated with different kinds of supports, furniture or the like, such as a crib, high chair, baby carriage or the like, and to provide means
- 20 whereby the improved holder may be associated with a portable support when it is not convenient to attach the same to an article of baby furniture.

A further object of the invention is to provide an improved holder, which is not only adaptable for holding nursing bottles, but which is also adapted for holding toys, such as rattles, balls or the like, in such a position that the same will always be 35 before the eyes of the infant and in such a position that the same can be hit by the infant.

A further object of the invention is to provide a novel joint connection for the 40 improved holder, whereby the same can be moved at any angle and held in a convenient and expedient manner.

A still further object of the invention is to provide an improved holder for baby 45 nursing bottles, toys or the like of the above character which is durable and efficient in use, one that is simple and easy to manufacture, and one which can be placed upon the market at a reasonable cost.

50 With these and other objects in view, the invention consists in the novel construction, arrangement and formation of parts as may be hereinafter more specifically described, claimed and illustrated in the ac-

companying drawings, forming a part of 55 this specification, in which:

Figure 1 is a perspective view of the improved support showing the same in operative position for supporting a bottle and in relation to a crib. 60

Figure 2 is a perspective view of the improved bottle support showing the same connected to a portable supporting base.

Figure 3 is an enlarged fragmentary detail perspective view of the inner end of the 65 supporting arm.

Figure 4 is an enlarged detail perspective view of the connecting joint utilized for connecting the supporting arm with the attaching hook, and 70

Figure 5 is an enlarged fragmentary detail perspective view of the inner end of the attaching hook.

Referring to the drawings in detail, wherein similar reference characters designate corresponding parts throughout the several views, the letter A indicates the improved milk bottle support which is adapted to be connected with a crib B or other article of baby furniture, such as a high 75 chair, carriage or the like.

The improved bottle support A comprises a supporting arm 10, which may be of any desired length and made from any desired material. The arm 10 has secured thereto 85 adjacent to its outer end, the substantially circular split clasp 11 which is adapted to detachably receive and hold a nursing bottle, shown in dotted lines in Figure 1 of the drawings. This clasp 11 may be secured in 90 place by a suitable pin 12 and if desired this clasp may be pivotally mounted upon the pin 12 so as to adjust the angle of the bottle in relation to the supporting arm. The inner end of the arm 10 has connected thereto 95 by means of an adjustable link 13 a hook 14, which is adapted to permit the supporting arm to be connected to a crib as shown in the drawings or a baby carriage, high chair or other support. The hook 14 includes arms 100 15 and a connecting bight portion 16 and the outer arm 15 is outturned as at 17 so as to facilitate the positioning of the same upon a bed or other support. This hook 14 is preferably formed of resilient metal, so 105 that the arms 15 will frictionally engage the article upon which it is placed. As shown in the drawings the same is placed in con-

nection with a crib which includes the usual longitudinal rail 18 upon which the hook is adapted to be placed. The inner arm 15 is provided with a right angular extending 5 foot 19 which forms the means by which the link 13 is utilized for connecting the hook to the arm 10. The link 13 includes a pair of spaced ears 20 and 21 which are adapted to receive between the same the right angularly 10 extending foot 19. The ears 20 and 21 and the foot 19 are provided with registering openings 22 which are adapted to receive a pivot pin. One end of the pivot pin is threaded for the reception of the thumb nut 15 23 and by tightening the nut the link 13 may be held in any preferred adjusted position on the hook 19. Disposed at right angles to the ears 20 and 21 is a reduced outwardly extending lug 24 and this lug 24 is adapted to 20 be disposed between a pair of spaced ears 25 and 26 formed on the inner end of the arm 10. These ears 25 and 26 are formed by bifurcating the inner end of the arm 10 as at 27. The ears 25 and 26 are provided with 25 registering openings 29 which are adapted to align with an opening 30 formed in the lug 24 and these openings are adapted to receive a suitable pivot pin upon which is threaded an adjustable thumb nut 31. By this construction, it can be seen that the arm 10 can be 30 swung in a vertical plane to any desired position and by tightening the thumb nut 31 this arm can be held in any desired adjusted position.

35 It is also desirable to permit the arm 10 to support a suitable toy such as a ball or rattle designated by the numeral 33. In order to support the toy, the outer end of the arm 10 is provided with a screw eye 34 and a suitable supporting cord 35 is threaded through the screw eye 34 and attached to the ball or rattle 33.

In use of the improved bottle support, the hook 14 is placed over a suitable support, such as the rail 18 of a crib B and the thumb nut 23 is loosened so as to permit the arm 10 to be swung in a horizontal plane to the desired position. This thumb nut 23 is then tightened. After the arm 10 has been 40 moved to the desired position in a horizontal plane, the thumb nut 31 is loosened and the arm 10 is adjusted in a vertical plane to the desired position so as to support the bottle at

the desired angle and height after which the thumb nut 31 is tightened. Thus it can 55 be seen that the bottle can be held in any desired position which can be conveniently reached by the infant and held against accidental displacement. This construction provides an exceptionally simple and durable means for holding the bottle and eliminates the trouble and inconvenience heretofore experienced in feeding an infant from a bottle.

In some instances where the support can 60 not be conveniently attached to a part of the crib or high chair a support 36 is utilized. This support 36 includes a vertically disposed standard 37 and a base plate 38. It can be seen that the support 36 can be placed 70 upon any flat surface, such as a table or the like, and the upper end of the standard 37 carries an outwardly extending pivot pin which is adapted to be placed in any one of a plurality of openings 39 formed in the arm 75 10 for that purpose. A wing nut 40 is threaded upon the pivot pin so that the arm 10 can be held in any desired position or angle in relation to the standard 37.

Changes in details may be made without 80 departing from the spirit or scope of this invention; but,

I claim:

A support for nursing bottles comprising an elongated arm, a U-shaped attaching clip 85 disposed at one end of the arm, the inner end of said arm being bifurcated to provide a pair of pivot ears, an inwardly extending pivot ear formed on the lower terminal of the inner leg of the clip, a connecting link 90 arranged intermediate the attaching clip and the mentioned end of the arm, said link including a longitudinally disposed vertically positioned pivot ear positioned intermediate the pivot ears formed on the inner 95 end of the arm, and a pair of spaced pivot ears arranged in horizontal plane for receiving the pivot ear formed on the clip, means pivotally connecting said pivot ears of the link, the clip and the arm together, a laterally extending bottle clip carried by the arm adjacent to its outer end, and means for 100 pivotally securing the bottle clip to its arm.

In testimony whereof I affix my signature.

FRANK DAVISON.
